UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT BREAKER.

Application filed March 15, 1922. Serial No. 543,909.

My invention relates to circuit breakers and particularly to the form and general arrangement of relatively movable contact members and the mechanism associated therewith.

The object of my invention is to provide a simple and effective form of breaker wherein in certain of the magnetic forces set up during the passage of current through the conductors and contact members are utilized to secure a more effective engagement between the relatively movable contact members, and to provide an improved form and arrangement of auxiliary contact members or arcing tips.

As shown in the accompanying drawings, Figure 1 is a view, in side elevation, of a portion of a circuit breaker in which my invention is embodied.

Fig. 2 is an end elevational view of the breaker shown in Fig. 1.

Figs. 3 and 4 are plan and side elevational views, respectively, of one of the arcing tips which I employ in my invention.

The device comprises two pairs of conductors 5 and 6, the conductors 5 being provided with main stationary contact members 7 and the conductors 6 with main stationary contact members 8. A bridging member 9 is operated by lifting rods 10 to open and close the circuit across the contact members 7 and 8.

The construction of the contact members 7 and 8 is identical, so that a description of one will suffice for both. Likewise, the construction of the main bridging member 9 is the same at both of its ends.

The contact members 8 serve as one pole of the circuit breaker and the contact members 7 constitute the other pole thereof. A cross-bar 12 is secured to the members 8 by screws 13 and serves as a support for the stationary arcing tips 14 that are carried by flexible members 15 through which a bolt 16 extends to secure them to the bar 12. Yielding members 17 serve to normally bias the tips 14 toward each other.

The bridging member 9 comprises side plates 18, between which brush members 19 are located, and a metal casting 20. Brush members 19 are securely clamped between the plates 18 and the casting 20, by the bolts 22, and the bridging structure is supported from the lifting rods 10 by bolts 23. The casting 20 is provided at each end with a shelf-like

portion to which an arcing tip 25 is secured by means of screws 26. It will be observed that the contact surfaces of the arcing tips 25 do not extend beyond the bridging member and that the arcing tips 25 are movable with the bridging member into and out of engagement with the flexibly supported yielding contact members 14.

The arcing tips 14 and 25 function in the usual manner to prevent the formation of arcs across the bridging member 9 and stationary contact members 7 and 8 upon their separation.

Assuming current to be flowing downwardly through the conductors 6, across the bridging member 9 and upwardly through the conductors 5, it will be seen that such current traverses two parallel paths and that the conductor members through which the current passes in traveling such paths are, therefore, attracted to each other. This action tends to bias the flared portion of the brush members 19 of the bridging member 9 toward each other, thus effecting a firmer engagement between such flared portions and the stationary contact members 7 and 8.

It is well known that, as the current through the conductors 5 and 6 is traveling in opposite directions, opposing magnetic forces are set up that tend to distort the flexible brush members and to break engagement between such brush members and the stationary contact members 7 and 8. This force is neutralized by the magnetic attraction of the divided brush members for each other, the flared portions being thereby biased inwardly, as above described.

It will be further observed that, by reason of the space provided between the flared portions of the brush members 19 of the bridging member 9, I am enabled to locate the arcing tips 25 between such flared portions and to thereby materially shorten the overall length of the bridging member that is ordinarily required in circuit breakers of the liquid type. The double-path construction of conductors permits the location of the stationary arcing tips 14 therebetween, in a position to co-operate with the movable arcing tips 25.

Various modifications and changes may be made herein without departing from the spirit and scope of the invention, as set forth in the appended claims.

The oppositely flared contact laminations

shown in this case constitute an invention claimed in my copending application 448,272.

I claim as my invention:

1. The combination, in a circuit breaker, of a pair of conductors provided with a stationary contact member constituting one pole of the breaker, a similar pair of conductors and contact member constituting another pole of the breaker, a bridging member provided with a pair of transversely flared portions, arcing tips located between such flared portions, and an arcing tip carried by each of the said conductors for co-operating with the last named arcing tips.
- 10 2. The combination, in a circuit breaker, of a divided conductor provided with spaced contact surfaces, an arcing tip located between such surfaces, a relatively movable

contact member provided with oppositely flared engaging surfaces and an arcing tip 20 located between such surfaces in a position to be engaged by the first mentioned arcing tip.

3. The combination, in a circuit breaker, of a divided conductor provided with spaced 25 contact surfaces, an arcing tip located between such surfaces, a relatively movable contact member provided with oppositely disposed yielding engaging surfaces, and an arcing tip located between such surfaces 30 in a position to be engaged by the first mentioned arcing tip.

In testimony whereof, I have hereunto subscribed my name this 10th day of March, 1922.

CHRISTIAN AALBORG.
